CLAIM

The ornamental design for a golf training aid, as shown and described.

DESCRIPTION

FIG. 1 is a perspective view of a golf training aid; FIG. 2 is a perspective view thereof in a state of use with disclaimed environmental subject matter;

FIG. 3 is a front view thereof;

FIG. 4 is a rear view thereof;

FIG. 5 is a top view thereof;

FIG. 6 is a bottom view thereof;

FIG. 7 is a left-side view thereof; and,

FIG. 8 is a right-side view thereof.

The dashed broken lines in FIGS. 1-8 depict portions of the golf training aid that form no part of the claimed design. The additional dashed broken lines in the form of three rods in FIG. 2 depict environmental subject matter and form no part of the claimed design. The dot-dashed broken lines represent boundaries of the claimed design and form no part of the claimed design.

1 Claim, 4 Drawing Sheets
